OTTO LAUBER, OF ESSEN-ON-THE-RUHR-HOLSTERHAUSEN, GERMANY,
ASSIGNOR TO FRIED. KRUPP, OF ESSEN-ON-THE-RUHR, GERMANY.

RECOIL-BRAKE FOR WHEELED GUN-CARRIAGES.

SPECIFICATION forming part of Letters Patent No. 791,347, dated May 30, 1905.

Application filed September 13, 1901. Serial No. 75,295.

To all whom it may concern:

Be it known that I, OTTO LAUBER, engineer, residing at 36 Grünstrasse, Essen - on - the - Ruhr-Holsterhausen, Germany, have invented certain new and useful Improvements in Recoil-Brakes for Wheeled Gun-Carriages, of which the following is a specification.

The present invention relates to that class of wheeled gun-carriages in which the gun-barrel recoils relatively to the carriage when the gun is fired. To avoid shocks in such ordnance either during the recoil or the running-out movement of the gun-barrel, which would cause the carriage to change its position, the recoil-brake must be so arranged that the gun-barrel can have what is termed a "long" recoil, the shortest length of which is about twelve times the caliber of the barrel. This, however, involves difficulties in the construction of the means required to return the barrel to its firing position. The means employed for this purpose in field-artillery with long barrel-recoil have been either a compressed-air or spring recuperator. The former recuperator has the great disadvantage that the air-cylinder on account of the high initial pressure under which the air has to stand is very difficult to be held air-tight and is therefore extremely liable to fail. With the second kind of recuperator the difficulties in the construction of springs for long recoil have not been heretofore surmounted in a satisfactory manner. In order to prevent the use of too long a spring, it has been necessary either to telescope several springs together (and even that arrangement extended backward beyond the breech) or to provide means for decreasing the stroke of the spring. In both cases considerable disadvantages arise—such as increased weight of the gun, disarrangements through the breakage of one of the telescoped springs, complicated construction of the ordnance, &c.—so that the manifold conditions imposed upon a gun in use in the field are not fulfilled.

The present invention aims to construct a recoil-brake for wheeled gun-carriages with long barrel-recoil in which in order to obviate the above-named difficulties the recoil

movement of the barrel is transmitted to the return-spring without reducing the stroke of the return-spring, and the latter will consist of a single spring-column of comparatively short length. This object is accomplished according to this invention by a helical return-spring whose cross-section in the direction of the axis of the spring has a less dimension than in the direction perpendicular thereto and which when incased and with its appurtenant parts is not longer than the gun-barrel, the spaces between the coils being so great that in firing the spring can be compressed at least twelve times the caliber of the barrel.

In the accompanying drawing, which illustrates one embodiment of the invention, a recoil-brake is shown in longitudinal section in which the recoil-spring is of rectangular cross-section.

The gun-barrel A is mounted on a slideway or cradle B in a known manner. Under the slideway is arranged the cylinder D of a hydraulic brake, which is of less length than the barrel and is rigidly connected by a screw S to the horn E of the breech of the barrel. Said screw S engages with the boss d of the brake-cylinder D and rests with its head against the horn E. The stem C of the brake-piston c is secured near the muzzle of the barrel at the front end of the slideway by means of a removable cap L and remains at rest during the recoil and running-out movement of the barrel, while the brake-cylinder follows the movements of the barrel. The brake-cylinder is encircled by the return-spring F, which rests at rear against a fixed abutment G, which guides the brake-cylinder, and at the front against a collar H of said brake-cylinder. The return-spring is of rectangular cross-section and consists of several (in the drawing four) parts, placed one behind another, which are separated from each other by the washers K. As seen in the drawing, the return arrangement does not extend out beyond the mouth of the barrel when in firing position, nor past the breech of the barrel. The spaces between the coils of the return-spring are so proportioned that the spring can take up a long recoil—i. e., can be com-

essed at least twelve times the caliber of the

Assembling the recoil-brake with the gun accomplished as follows: After the returning has been shoved onto the brake-cylinder the latter is by compression of the ing from the front end shoved under the leway of the barrel until the screw S, with head against the horn E, can engage the male thread of the cylinder-boss d. Then screw is turned in until the boss d passes through the abutment G into the opening in horn E and the brake-cylinder comes in alignment with the latter. The return-spring thereby brought into initial tension at the same time. Finally the piston, if it has not already done, is introduced into the cylinder, the front part of the latter seated, and the piston-rod by means of cap L secured to the slideway or cradle. The steps in the disassembling of the brake in the gun are accomplished in reverse order.

The operation of the recoil-brake can be easily seen from the drawing.

If the barrel recoils on firing, it carries the cylinder along with it, so that the return-spring is put under tension. The recoil finished, the spring brings the barrel back again into the firing position. The hydraulic brake provided by the piston and cylinder acts as a check to graduate these movements in the well-known manner.

The advantages of the foregoing recoil-brake are in the main as follows: The returning, by reason of its cross-sectional form, bows under otherwise equal conditions of its being compressed into a shorter space than the rings of circular cross-section heretofore used for guns with long recoil of the barrel, and is therefore able to take up a long recoil, and of comparatively short length itself. Furthermore, on account of its division, it can easily be produced and any damaged parts can be replaced. Besides this advantage is the fact that substitute pieces can be carried along in little space. The arrangement of the return-spring on the brake-cylinder renders the spring readily accessible, provides a good idea therefore, and protects the hydraulic brake against flying fragments of shot, &c., when an open slideway or cradle is used. The connection of the brake-cylinder with the barrel by a screw, which serves at the same time to secure the return-spring under initial tension, facilitates the putting together and taking apart of the brake and obviates the necessity of carrying along a special tension-screw. Furthermore, the present recoil-brake, in consequence of the connection of the brake-cylinder with the breech of the barrel permits ready removal of the brake, an easy exchange of the brake-cylinder, and a quick replacement of the piston-packing, the latter without taking off the brake-cylinder from the gun.

Moreover, the barrel after removal of the tightening-screw can be withdrawn from the slideway and replaced by another without disturbing the recoil-brake. Obviously the return-spring could have any other section than a rectangular that would fulfil the above-recited conditions—as, for example, an elliptical or a lenticular section.

Having thus described my invention, what I claim as new, and desire to secure by Letters Patent, is—

1. In combination with a portable gun having a long barrel-recoil, a recoil-brake having a helical return-spring formed in a single column with the cross-section of the coils, in the direction of the axis of the spring, of a less dimension than in a radial direction, compressible the length of the entire recoil and at least twelve times the caliber of the gun.

2. In combination with a portable gun having a long barrel-recoil, a recoil-brake having a helical return-spring formed in a single column with the cross-section of the coils, in the direction of the axis of the spring, of a less dimension than in a radial direction, compressible the length of the entire recoil and at least twelve times the caliber of the gun, and having a length not exceeding the length of the gun-barrel.

3. In a portable gun having a barrel recoil-ing at least twelve times the caliber of the gun, the combination with the mount and the barrel, of an abutment fixed relatively to the barrel, and an abutment fixed relatively to the mount, and a helical return-spring having a length not exceeding the length of the barrel, formed in a single column with its coils of a cross-section less in the direction of the axis of the spring than in a radial direction, engaged by the two abutments, and compressible at least twelve times the caliber of the gun.

4. In combination with a portable gun having a long barrel-recoil, a recoil-brake having a helical return-spring of a strength sufficient to absorb the entire recoil, formed in a single column with the cross-section of the coils, in the direction of the axis of the spring, of a less dimension than in a radial direction, compressible at least twelve times the caliber of the gun, and having a length less than the length of the gun-barrel.

5. A portable gun having a long barrel-recoil, the combination with the mount and the barrel, of an abutment fixed relatively to the barrel, and an abutment fixed relatively to the mount, and a single helical return-spring absorbing the entire recoil, having a length less than the length of the barrel, formed in a single column with its coils of a cross-section less in the direction of the axis of the spring than in a radial direction, engaged by the two abutments, and compressible at least twelve times the caliber of the gun.

6. In a recoil-brake, the combination with

the gun and its mount upon which it recoils, of a braking-cylinder and its piston, an abutment at the fore end of the braking-cylinder, a fixed abutment at the mount, a helical return-spring 5 of a strength sufficient to absorb the entire recoil surrounding the cylinder and bearing with its fore end against the abutment of the cylinder and with its rear end against the fixed abutment, the coils of said spring being of greater dimension in a radial direction than in the direction of the axis of the spring and having spaces between them which aggregate at least twelve times the caliber of the gun, and means in the rear of the fixed abutment 15 securing the braking-cylinder and the gun together.

7. In a recoil-brake, the combination with the gun, and its mount upon which it recoils, of a braking-cylinder and its piston, an abutment 20 in which the brake-cylinder is guided, a return - spring surrounding the cylinder and bearing against the abutment, and means in the rear of the abutment securing the braking-cylinder and the gun together, and placing tension upon the spring when the parts are assembled.

8. In a recoil-brake, the combination with the gun, and its mount upon which it recoils, of a braking-cylinder and its piston, an abutment 25

in which the brake-cylinder is guided, a return - spring surrounding the cylinder and bearing against the abutment, a horn depending from the gun in the rear of the abutment and receiving the end of the braking-cylinder, and a screw rigidly securing together the rear 30 end of the cylinder and the horn of the gun, and placing tension upon the spring when the parts are assembled.

9. In a recoil-brake, the combination with the gun, and its mount upon which it recoils, of a brake-cylinder provided with a rear extension having a screw-threaded opening, an abutment in which the brake-cylinder is guided, a return-spring surrounding the cylinder and bearing against the abutment, a horn depending from the gun in the rear of the cylinder, and having an opening receiving the extension of the brake-cylinder, and a screw rigidly 40 securing together the rear end of the cylinder and the horn of the gun, and placing tension 45 upon the spring when the parts are assembled.

In testimony whereof I have hereunto set my hand in the presence of two subscribing witnesses.

OTTO LAUBER.
